UNITED STATES PATENT OFFICE.

FREDERICK W. GRELL, OF NEW YORK, N. Y., ASSIGNOR TO AMERICAN HARD RUBBER COMPANY, OF NEW YORK, N. Y., A CORPORATION OF NEW YORK.

DESIGN FOR A COMB.

43,567.

Specification for Design.

Patented Feb. 18, 1913.

Application filed November 21, 1911. Serial No. 661,606. Term of patent 14 years.

To all whom it may concern:

Be it known that I, FREDERICK W. GRELL, a citizen of the United States, residing at College Point, borough of Queens, city of New York, and State of New York, have invented a new, original, and ornamental Design for Combs, of which the following is a specification, reference being had to the accompanying drawing, forming part thereof.

Figure 1 is a side view of the comb embodying my new design. Fig. 2 is an edge view looking toward the teeth of the comb.

Fig. 3 is an edge view looking toward the back of the comb.

I claim:

The ornamental design for a comb, as shown.

In testimony whereof I have signed this specification in the presence of two subscribing witnesses.

FREDERICK W. GRELL.

Witnesses:

HENRY W. RAU,
LOUIS RUCKDASCHEL.
